(57) CLAIM

The ornamental design for a drinking container holder, as shown and described.

DESCRIPTION

FIG. 1 is an upper perspective view of the drinking container holder showing my design.

FIG. 2 is a front elevation view thereof;

FIG. 3 is back elevation view thereof;

FIG. 4 is a side elevation view thereof;

FIG. 5 is an opposite side elevation view thereof;

FIG. 6 is a top plan view thereof;

FIG. 7 is a bottom plan view thereof;

FIG. 8 is an upper perspective view thereof showing a cup being positioned within the holder; and,

FIG. 9 is an upper perspective view thereof showing a water bottle being positioned within the holder.

Broken lines are for illustrative purposes and form no part of the claimed design.
